BEVERAGE DISPLAY RACK

Alfred W. Goodman, San Francisco, Calif.

Application April 19, 1954, Serial No. 30,066

Term of patent 3½ years

(Cl. D80—9)

Fig. 1.

Fig. 2.

Fig. 3.

Fig. 4.

To all whom it may concern:

Be it known that I, Alfred W. Goodman, a British subject and citizen of Canada, residing in the city and county of San Francisco, State of California, have invented a new, original, and ornamental Design for a Beverage Display Rack, of which the following is a specification, reference being had to the accompanying drawing forming a part thereof.

Fig. 1 is a front elevational view of a beverage display rack showing my new design;

Fig. 2 is a side elevational view thereof;

Fig. 3 is a top plan view; and

Fig. 4 is a bottom plan view thereof.

I claim:

The ornamental design for a beverage display rack, as shown.
